UNITED STATES PATENT OFFICE.

CARL FRIEDRICH WOLFGANG ZÖLLER, OF ALTONA-OTTENSEN, GERMANY,
ASSIGNOR TO THE FIRM OF ALFRED GUTMANN ACTIEN GESELLSCHAFT
FÜR MASCHINENBAU, OF ALTONA-OTTENSEN, GERMANY.

MEANS FOR REMOVING DUST.

No. 821,776.

Specification of Letters Patent.

Patented May 29, 1906.

Application filed June 28, 1905. Serial No. 267,420.

To all whom it may concern:

Be it known that I, CARL FRIEDRICH WOLFGANG ZÖLLER, a subject of the German Emperor, and a resident of Altona-Ottensen, Germany, have invented certain new and useful Improvements in Means for Removing Dust, of which the following is a specification.

In cleaning as hitherto carried out by means of a free jet (a sand-jet) in closed work chambers or rooms a great defect has been that even high work rooms or halls have been filled with dust to such an extent that even after the work had proceeded for but a short time it was found impossible to continue it. This defect is especially noticeable in what are termed "cleaning-houses," in which the dust is drawn out through the grating-like floor of the house or chamber by means of an exhauster, while through roof-openings, uniformly distributed throughout the roof, fresh air is supplied. This method does not, however, succeed in obviating the said defect, the reason for this being, as careful experiments have now demonstrated, that in the first place owing to a displacement of air throughout the entire chamber the dust coming from the article cleaned with the free jet and from the jet itself is distributed throughout the chamber and increases according to the increase in size of the article treated, and in the second place because owing to the size of the chamber and to the cost only a relatively small displacement of air can be created which is insufficient to speedily carry away the large mass of dust produced. In addition to this the dust drawn through the bottom grating mixes with the sand employed for cleaning unless special steps are taken to prevent this, as this sand is usually allowed to fall through the grating also in order that it may be reconducted to the sand-jet apparatus. A recognition of these defects in removal of dust as hitherto carried out formed the basis for the present invention, which consists, broadly, in conducting air at high pressure through one or more zones only of the cleaning-chamber, thereby creating one or more through-currents of air and not merely an exhaustion of air, the said air current or currents being directed to pass the operative and above the article to be cleaned.

A cleaning house or chamber constructed in accordance with this invention is shown on the accompanying sheet of drawings, and described hereinafter by way of example.

Figure 1 is a vertical, and Fig. 2 a horizontal, sectional view of a cleaning-house made in accordance with and embodying the invention.

Similar characters refer to similar parts throughout both the views.

The two walls 1 and 2 of the cleaning-chamber between which the work place—that is to say, the place for the article 3 to be cleaned—and the stand 4 for the operative are provided with two oppositely-situated openings *a'* and *a''*, which are preferably arranged at such a height that a current of air passing in the direction of the arrows from one opening to the other or from one set of openings to the other passes beside the operative at a lower level than his respiratory organs and above the highest article treated. Outside the opening *a'* is fitted a socket *b*, which by means of a pipe *c* is connected with a powerful air-exhauster, by means of which air may be sucked through the zone of the cleaning-chamber situated between the aforesaid openings in order to carry all the dust from this zone to the exterior.

In front of the air-exhauster a dust-filter consisting either of a mechanical filter or a water-bath may be arranged in the known manner in order to protect the exhauster from dust. In the known manner likewise the floor *d* of the chamber may be perforated, and beneath it may be mounted a conveyer-worm *e*, leading to an elevator in order to reconduct the used sand which falls through the floor back to the sand-jet apparatus.

In place of sucking the air through the chamber it may be forced through it; but forcing is less advantageous than suction.

In accordance with the novel process, therefore, a current of air—that is to say, an air-bearing stratum—is produced only where the removal of the dust is required, and it does not entail any difficulty or considerable cost to impart a very high velocity to this air-current or air stratum, and by this means the dust is certainly removed from the zone traversed by the current. The operative may

be protected from drafts by means of suitable clothing—for example, by means of a head-covering extending down the neck.

Having fully described my invention, what 5 I claim, and desire to secure by Letters Patent, is—

A device of the character specified, comprising a chamber having openings in the walls arranged opposite to one another, o means for mounting an article to be cleaned below said openings, a perforated floor in said

chamber, a free sand-jet in the latter, and an air-exhaust in communication with one set of openings for the purpose of establishing an air-current zone at a lower level than the respiratory organs of an operator of the sand-jet and above the highest article to be cleaned.
